UNITED STATES PATENT OFFICE.

PETER MADSEN, OF CHICAGO, ILLINOIS, ASSIGNOR TO O. JAY SMITH, OF CHICAGO,
ILLINOIS.

VALVE-TOOL.

Specification of Letters Patent. Patented Feb. 15, 1921.

1,368,446.

Application filed March 31, 1919. Serial No. 288,369.

To all whom it may concern:

Be it known that I, PETER MADSEN, a citizen of the United States, and a resident of the city of Chicago, in the county of Cook 5 and State of Illinois, have invented certain new and useful Improvements in Valve-Tools; and I do hereby declare that the following is a full, clear, and exact description of the same, reference being had to the accompanying drawings, and to the numerals of reference marked thereon, which form a part of this specification.

In removing or mounting split washers or pins for engine valves considerable trouble 15 is often experienced, caused primarily by slipping of the tool used in holding the strong valve spring compressed, thereby releasing the valve spring and causing injury to the person making the valve changes.

20 To obviate accidental injuries when engine valve washers or pins are being replaced, an improved type of an engine valve tool has been devised, whereby engine valve washers or pins may be conveniently removed or mounted in place without subjecting a person making the change to accidental injuries.

It is an object of this invention to provide an improved engine valve tool permitting convenient mounting or removal of 30 washers or pins.

Another object of the invention is the construction of an engine valve tool wherein clamping jaws are adapted to be adjusted by a slidable member to engage around a clamp, and then release an engine valve pin.

It is also an object of the invention to construct an engine tool having a member slidably engaged on the clamping arms 40 whereby the clamping jaws at the end of said arms are adapted to securely clamp an engine valve pin therebetween when the member is slid rearwardly a certain distance, a continuation of said rearward movement causing the clamping jaws to move apart to release the pin.

A further object of this invention is the construction of a tool wherein connected clamping tongs have a member slidable 50 thereon and adapted by movement on said tongs to engage around, clamp, and then eject a nut or washer.

It is an important object of this inven-

tion to provide a simple and effective tool adapted primarily for mounting and removing engine valve pins or washers without subjecting an operator to accidental injuries due to slipping of the engine valve springs.

Other and further important objects of 60 the invention will be apparent from the disclosures in the specification and drawings.

The invention (in a preferred form) is illustrated in the drawings and hereinafter 65 more fully described.

On the drawings:

Figure 1 is a top plan view of a tool embodying the principles of this invention;

Fig. 2 is a side view thereof;

Fig. 3 is a sectional view taken on line 70 3-3 of Fig. 1;

Fig. 4 is a plan view of the tool showing the slide member in position releasing an engine valve pin;

Fig. 5 is a view of the clamping end of the 75 tool showing the operation in dotted lines;

Fig. 6 is a plan view of a modified form of the device; and

Fig. 7 is a section taken on the line 7-7 80 of Fig. 6.

As shown on the drawings:

The tool comprises a flexible looped metal strap 1, the ends of which converge or are bent toward one another to form pivoted arms or tongs 2, the free ends of which are 85 curved outwardly to afford jaws 3. The ends of the jaws are bent to form gripping flanges 4.

Disposed within the metal loop 1, which forms the handle of the tool, is a slidable 90 adjusting member embracing a metal strap formed as shown in Fig. 1, to provide a finger loop 5, formed in the bight end of said member, between side arms 6, the forward portion 7 of which converge with the 95 ends bent to lie adjacent one another to form an ejecting tip 8. As shown the slid- able member 5-8 may be formed of one piece of metal if desired.

To hold the slidable member engaged 100 within the handle, channel shaped guides 9 are integrally formed or rigidly secured near the forward ends of the arms 6. Each guide 9 has the ends thereof bent over the edges of the respective tongs 2, as shown in 105 Figs. 1 and 2. The slidable member is thus

adjustably disposed within the handle and in sliding engagement with the tongs 2, whereby the clamping jaws 3—4 are adapted to be operated depending upon the movement of the slidable member.

As shown in Fig. 4, the reference numeral 10 indicates an engine valve pin, in released position between clamping jaws of the tool. A split or open engine valve washer 11 is shown in Fig. 5, clamped between the rounded jaws 3, in position to be ejected by the ejector 8, when the slidable member is moved forwardly to cause separation of the jaws as shown by the dotted lines.

Figs. 6 and 7 show a modified form of tool in the form of a wrench and comprising a rigid metal arm or tong 12, having integrally formed on one end thereof a transversely passaged head or collar 13, on which is pivotally mounted by means of a pivot pin or bolt 14, one end of an arm or tong 15. Integrally formed on the free end of each of the tongs 12 and 15 is a jaw 16, provided with a notch 17. The notches 17 are disposed opposite each other to permit a nut to be easily gripped between the jaws 16.

A slidable member is movably engaged on the tongs 12 and 15, to facilitate operation of the clamping jaws. The slidable member embraces a U-shaped or channel-shaped metal base 18, having integrally formed centrally on the interior thereof a rib or boss 19, the upper end of which is flat and disposed in the plane of the upper ends of the base sides. A top piece or plate 20 is removably secured across the top of the base by means of screws 21, which thread into the boss 19. As shown in Fig. 7, the tongs 12 and 15 are positioned on opposite sides of the boss 19. Movement of the slidable member on the wrench tongs serves to move the wrench jaws 16 to either engage or release a nut.

The operation is as follows:

To insert a pin in the apertured projecting stem of an engine valve the tool is adjusted to separate the jaws 3—3, by gripping the tool by the handle 1, with the forefinger of the person's hand projecting through the finger loop 5 of the slidable member and moving said member forwardly by the forefinger. The open jaws are placed on opposite sides of the pin 10, and the slidable member 5—8 is pulled rearwardly by the forefinger to an intermediate or middle position of adjustment in which the guide members 9, slidable upon the tongs 2, have forced the clamping jaw gripping flanges 4 tightly together to securely grip the pin 10. In the intermediate position of the slide member the tong portions 22 contact each other. The pin thus held secured between the jaw flanges 4, is next inserted through

the opening in the projecting upper end of the engine valve stem, the spring of the engine valve first being held compressed by any suitable tool. To release hold of the pin 10, after it has been inserted through the valve stem, the slide member 5—8 is pulled rearwardly still farther into a rear position of adjustment, shown in Fig. 4. This last movement of the slide member acts to force the tong portions 22 more tightly together, flexing the portions between 22 and the handle 1. This will cause the portions 3 and 4 to rotate about the contacting ends of 22 as a pivot and open the gripping flanges 4, whereby the pin 10 is released and the tool removed from engagement with the engine valve parts. The engine valve spring is then released.

To remove a pin from an engine valve the engine valve spring is first compressed and the slide member of the tool is moved to its forward position to separate the jaws which are then engaged on opposite sides of the pin. The slide member 5—8 is then pulled rearwardly into its intermediate or locking position, wherein the jaws are forced together to clamp the pin therebetween. The pin is then removed by simply pulling the same out of the valve stem opening.

In using the improved tool for mounting or removing an engine valve pin, it will be particularly noted that the fingers of a person performing the operation are not brought into close engagement with the engine valve parts, and as a consequence are protected against injury should the tool, holding the valve spring compressed, be accidentally released to allow the spring to snap back into normal position.

As shown in Fig. 5, the tool is disclosed having a split engine valve washer 11, clamped between the jaws 3. To release the washer after it has been positioned around an engine valve stem, the slide member 5—8 is moved forwardly from the full-line position shown in Fig. 5, until the guides 9 engage the jaws 3. This movement of the slide member causes the tip 8 to contact and eject the washer 11 from between the jaws.

In the modified wrench form of the device, shown in Fig. 6, the pivotally connected tongs 12 and 15 are adjusted with respect to each other by sliding the slide member 18—20 forwardly or rearwardly to adjust the jaws 16 to either grip or release a nut. Forward movement of the slide member will cause the boss 19 to separate the jaws 16, to permit the same to engage on opposite sides of a nut. To grip the nut to permit rotation thereof, the slide member is moved rearwardly thereby forcing the jaws together.

Numerous details of construction may be varied through a wide range without departing from the principles of this invention.

tion, and it is therefore not purposed to limit the invention granted otherwise than necessitated by the prior art.

I claim as my invention:

- 5 1. A tool comprising a loop of resilient material, jaws integral with the sides of said loop at the free ends thereof, portions of the sides of said loop converging toward their free ends, a sliding member engaging said 10 converging portions, each side of said loop having a part between the converging portion and the jaw whereby motion of the sliding member away from the jaws will cause the jaws to approach and to grasp whatever 15 object is between them, further motion of the sliding member in the same direction will cause the nearer ends of the converging portions to contact, and still further motion of the sliding member in said direction will 20 cause the jaws to open.
2. A tool of the class described comprising a pair of connected converging clamping members, and substantially elliptical adjusting means slidably engaged thereon, and 25 means coöperating therewith whereby when the adjusting means is moved rearwardly from a forward opening position to an intermediate position said members will be 30 clamped together and when it is moved to a rear position said members are again separated.
3. A tool comprising connected members having clamping jaws at the free ends thereof, means including cam surfaces converging 35 toward said free ends and a member slidably engaging said surfaces, whereby, when said sliding takes place in one direction up to a predetermined point, the jaws will approach each other, and means coacting with said 40 first-named means to cause said jaws to recede from each other when said sliding continues in the same direction beyond said point.
4. A tool comprising a pair of movably 45 connected members converging forwardly to a point of engagement, jaws on the free ends thereof, and an adjusting means slidably engaging said members and adapted to be moved forwardly from a rear position, 50 wherein said members contact each other and said jaws are separated, to an interme-
- diate position wherein the members and said jaws both respectively engage each other, further forward movement of said means acting to separate both the jaws and 55 said members.
5. A tool embracing a pair of resilient tongs, clamping jaws at the free ends thereof, a finger operated member slidably engaged with said tongs to adjust said jaws 60 with respect to each other, and an ejector on said member and actuated thereby to contact with the object held by the jaws to eject the same.
6. A tool embracing a looped resilient handle, resilient arms formed thereon, jaws integral with the free ends of said arms, manually operable means slidably engaged on said arms within said handle, and an ejecting tip formed on said means adapted 70 to push an article from between said jaws when the jaws are separated by movement of said means.
7. A tool comprising a looped resilient handle, converging arms formed thereon, 75 jaws on the free ends of said arms, and adjusting means slidable between the arms, said adjusting means converging toward the jaws and toward the handle.
8. The combination with a pair of clamping members, of means slidable between said members for adjusting the same, and means on the slidable means between the clamping members acting to force the clamped object 80 from between the members. 85.
9. A pair of tongs, means slidable between the members of said pair for adjusting them, and means controlled by the first-named means for thrusting away the object held by the tongs. 90
10. A pair of tongs, a carriage slidably mounted on both members of said pair, and a member carried by the carriage and thrust between the free ends of the tongs upon travel of the carriage toward said ends. 95
- In testimony whereof I have hereunto subscribed my name in the presence of two subscribing witnesses.
